UNITED STATES PATENT OFFICE.

HENRY CLAY JOHNSON, OF MEADVILLE, PENNSYLVANIA.

CORPSE COOLER AND PRESERVER.

SPECIFICATION forming part of Letters Patent No. 328,686, dated October 20, 1885.

Application filed August 10, 1885. Serial No. 173,985. (No model.)

To all whom it may concern:

Be it known that I, HENRY CLAY JOHNSON, a citizen of the United States, residing at Meadville, in the county of Crawford and State 5 of Pennsylvania, have invented a new and useful Improvement in Corpse Coolers and Preservers, of which the following is a specification.

My improved corpse cooler and preserver is constructed with a coiled pipe of tin or other metal, or of rubber or other suitable material, within a box or receptacle for the body, combined with a condenser, generator, or receiver for containing a suitable cooling 15 medium—as, for example, compressed ammonia or carbonic-acid gas—which is allowed to expand from the receiver or condenser within the said pipes to produce the desired refrigerating effect.

Under my improved construction the pipes are not used for holding condensed gas under 20 pressure, and hence do not require to possess special strength; consequently they may be made of cheap material, as above suggested.

The discharge end of the cooling-coil connects, through the medium of a check-valve, 25 with a water-tank, in which the ammoniacal gas is received and condensed in customary manner. The coiled pipe is moreover provided 30 with stop-cocks where it enters and leaves the cooling box or chamber, so that the cooling medium may be imprisoned for any desired length of time within the coil, and may be so held while the gas-holder and the water- 35 tank or either of them are detached. A dial-cock is also provided to accurately regulate the supply of cooling gas from the gas-holder; also, a thermal valve connected with the coil within the cooling-chamber, which may be set 40 to automatically regulate the refrigerating action to any desired degree of temperature.

As the great desiderata for preventing decomposition of all animal and other bodies are low temperature and freedom from moisture 45 in the surrounding air, I employ detachable dehydrating appliances in connection with the cooling-pipes, consisting of annular chambers made of gauze or perforated metal, adapted to be easily applied or detached and to contain 50 common salt, chloride of lime, or other deliquescent substance to take up and absorb moisture from the air. These annular dehy-

drating-chambers for the reception of deliquescent material are made in two parts hinged together, so as to adapt them to be clasped 55 around the cooling-pipes or removed therefrom at will, and are provided at one or both ends with stoppered apertures for the introduction or removal of the salt.

In the accompanying drawings, Figure I is 60 a perspective view of a corpse cooler and preserver illustrating my invention. Fig. II is a perspective view of the cooling-board used in connection therewith. Fig. III is a side elevation of a cooling-board in use. Fig. IV 65 is a detail view of the thermostat on a larger scale. Fig. V is a perspective view of one of the dehydrating-cylinders detached on a larger scale. Fig. VI is a transverse section of the same applied to the pipe, also on a larger 70 scale.

The case or box 1 may be of any suitable form. The cooling-pipe 2 surrounds its interior in any necessary number of coils, both of the extremities of said coiled pipe projecting preferably from one end of the case or box. The induction end is connected through the medium of a detachable hose or pipe, 3, with a receiver or gas-holder, 4, adapted to contain ammoniacal or other gas under pressure and to supply it as a cooling medium as rapidly as necessary, under control of a stop-cock, 13, having a dial-indicator, 14, to accurately regulate the flow. Stop-cocks 5 are provided in the projecting ends of the pipe 80 close to the box 1 for the purpose of imprisoning the gas in the coil 2 whenever this may be desirable. The discharge end of the pipe communicates through a detachable hose or pipe, 6, with a water-tank, 4^a, in which the 85 ammoniacal gas is received and condensed in customary manner, a check-valve, 15, being provided to prevent the reflux of gas or influx of water within the pipe 6 or 2, and the receiving-nozzle of the water-tank being furthermore provided with a simple stop-cock, 16, by which it may be opened or closed at will.

17 represents a valve within the cooling-chamber 1, (preferably located near the induction end of coil 2,) regulated by a thermostat, 18, so as to automatically control the temperature within the cooling-box to any degree to which the said thermostat may be set.

The construction of the thermostat is shown in detail on a larger scale in Fig. IV, 19 being a cylinder for the reception of mercury or other fluid expansible by heat, 20 a piston working therein, having a piston-rod, 21 22, divided into two parts, screwing one within the other, so as to regulate the effective length of the rod. This piston-rod connects with a lever, 23, fulcrumed at 24, and having on its free end a segment-rack, 25, gearing with a pinion, 26, on the spindle of the thermal valves 17. A spring, 27, presses the piston down against the expansive action of the fluid, so as to keep it in constant contact therewith. A milled head, 28, is provided on the adjustable rod 22 for screwing it up or down in the piston-rod 21, to regulate the length, as aforesaid.

The dehydrating appliance consists of an annular jacket constructed with an outer shell, 29, preferably of cylindrical form, divided longitudinally into two parts, connected at one side by hinges 30 and fastened together on the opposite side by suitable clasps, 31. Concentric with this outer tube, 29, is an inner tube, 32; also made in two parts, which are permanently connected to the respective parts of the outer tube, 29, by longitudinal plates 33, which meet face to face when the connected semi-annular receptacles are clasped around the pipes. The ends of the chambers formed between the concentric semi-cylindrical perforated or gauze tubes 29 32 are closed by semi-annular plates 34, permanently connected to the respective semi-cylindrical tubes 29 32 and to the longitudinal plates 33. Within these end plates, 34, are apertures closed by corks or other stoppers 35, to permit the ready insertion and removal of the salt or other deliquescent material. The tubes 29 32 and end plates, 34, may be made of perforated sheet metal, or either or all of them may be made of wire-gauze, if preferred.

The mode of using the invention will be clearly understood from the above description. The inner tube or cylinder, 32, tightly clasping the cooling-conduit 2, insures close contact therewith, so that the deliquescent salt is effectually cooled throughout its body, while the perforated or reticulated outer shell, 29, permits the air to be cooled and dehydrated to penetrate throughout the body of deliquescent salt contained therein. The heat and moisture in the said air are rapidly taken up and the vapor condensed by contact with the intensely cold deliquescent matter and quickly absorbed thereby, so that the air is reduced to a dry state at a very low temperature, bringing it into the best possible condition for preserving the body contained within the chamber.

Any suitable and well-known material may be used for dehydrating the air by absorbing the moisture therefrom—as, for example, chloride of sodium, chloride of calcium, or magnesia, caustic soda, &c.

Chambers of flat or any other desirable

shape may be substituted for the coiled pipe 2 for containing the cooling medium.

By the means provided as described above for connecting or disconnecting the cooling pipe with the gas-holder at one end and the water-tank or condenser at the other and closing the ends of the pipe, I am enabled with great facility to imprison the gas within the cooling-coil and remove the apparatus fully charged from place to place, as may be desirable; or to replace gas-holders and condensers which have been used with fresh ones as often as required when bodies are to be preserved for protracted periods.

The cooling-boards illustrated in Figs. II and III are made as fully described in Letters Patent No. 311,764, granted to me February 3, 1885.

Having thus described my invention, the following is what I claim as new therein and desire to secure by Letters Patent—

1. The combination of the corpse-receiving case or box 1, cooling-conduit 2, placed directly within the corpse-receiving chamber, 90 the gas-holder 4, the dial-cock 13 14, and the stop-cocks 5 5*, as and for the purposes described.

2. The combination of the corpse-receiving case or box 1, the cooling-conduit 2, placed directly within the corpse-receiving chamber, the gas-holder 4, the condensing water-tank, and the detachable hose or connecting-pipes 3 6, as and for the purposes described.

3. The combination of the corpse-receiving case or box 1, the cooling-conduit 2, the gas-holder 4, and the thermal regulator consisting of a valve, 17, and a thermostat controlling the same by the temperature within the corpse-receiving chamber, as herein explained.

4. The combination of the corpse-receiving case or box 1, the cooling-conduit 2, the gas-holder 4, detachable hose or connecting-pipes 3 6, and check-valve 15, as and for the purposes set forth.

5. A corpse cooler and preserver consisting of a receiving case or box, 1, a cooling-conduit, 2, placed directly within the corpse-receiving chamber, the detachable gas-holder 4, and the detachable dehydrating jackets 29 32, 115 clasped around the cooling-pipes within the corpse-receiving chamber, as explained.

6. A dehydrating-jacket for refrigerating-pipes, constructed, as herein described, of concentric semi-cylindrical shells of gauze or perforated material to permit the passage of air, connected by longitudinal plates, so as to form two semi-annular chambers adapted to be clasped around the refrigerating-pipe, and provided with stoppered apertures for the introduction and removal of deliquescent material.

HENRY CLAY JOHNSON.
